PAGE 2

FIG. 3

FIG. 4

FIG. 6

FIG. 5

FIG. 1 is a top plan view of a trailer type fertilizer spreader embodying my new design;

FIG. 2 is a left side elevational view thereof;

FIG. 3 is a right side elevational view thereof;

FIG. 4 is a front elevational view thereof;

FIG. 5 is a rear elevational view thereof; and

FIG. 6 is a left rear perspective view thereof.

In FIG. 1 the tongue portion has been broken away for convenience of illustration, and in FIGS. 2, 3, and 6 part of the tongue portion is shown only fragmentarily for convenience of illustration.

Dominant features of my design reside in the full line portion of the drawings.

I claim:

The ornamental design for a trailer type fertilizer spreader, as shown and described.
